(57) **CLAIM**

The ornamental design for a device cover, as shown and
described.

DESCRIPTION

FIG. 1 is a view from above of the device cover of the
subject disclosure;

FIG. 2 is a bottom side view of the device cover of FIG. 1;

FIG. 3 is a top side view of the device cover of FIG. 1;

FIG. 4 is a right side view of the device cover of FIG. 1;

FIG. 5 is a left side view of the device cover of FIG. 1;

FIG. 6 is a top view of the device cover of FIG. 1 in its open
position;

FIG. 7 is a right side perspective view of the device cover
of FIG. 6;

FIG. 8 is a perspective view from above of the design cover
of FIG. 6; and,

FIG. 9 is a perspective bottom view of the device cover of
FIG. 6 in an open position.

The broken lines represent portions of the structure that
forms no part of the claim. The boundary lines represent the
boundary of the claim.
